(57) **CLAIM**

The ornamental design for a glove-to-garment sleeve connector, as shown and described.

DESCRIPTION

FIG. 1 is a side elevation view of a glove-to-garment sleeve connector, the opposite side being a mirror image thereof; FIG. 2 is a perspective view thereof, shown from one end; and,

FIG. 3 is a perspective view thereof, shown from the end opposite that shown in FIG. 2.
